(57) **CLAIM**

The ornamental design for a lighting fixture for a passenger carrying car, as shown and described.

DESCRIPTION

FIG. 1 is a right-side elevational reference view of a representative rail car which indicates the locations subsequent views;

FIG. 2 is top plan reference view of the representative rail car and which indicates the locations subsequent views;

FIG. 3 is a cross-sectional view along line '3 in FIG. 1 and line 3 in FIG. 2 showing the lighting fixture for a passenger carrying car;

FIG. 4 is an enlarged view of the area 4 in FIG. 3;

FIG. 5 is a cross-sectional view along line 5 in FIG. 1;

FIG. 6 is an enlarged view of the area 6 in FIG. 5;

FIG. 7 is a cross-sectional view along line 7 in FIG. 5; and,

FIG. 8 is an enlarged view of the area 8 in FIG. 7.

The broken lines depict environmental subject matter only and form no part of the claimed design. The dot-dash chain lines indicate boundaries of the claimed subject matter and form no part of the claimed design. The dot-dot-dash chain lines indicate enlargement areas and form no part of the claimed design.
